UNITED STATES PATENT OFFICE.

JOHN STANLEY MORGAN AND DOUGLAS RIDER, OF LONDON, ENGLAND, ASSIGNEES
TO THERMAL INDUSTRIAL AND CHEMICAL (T. I. C.) RESEARCH COMPANY LIMITED, OF LONDON, ENGLAND.

DISTILLATION OF TAR.

Application filed June 1, 1922, Serial No. 565,102, and in Great Britain June 7, 1921.

The chief difficulties in the distillation of tar occur in the early and final stages. At first the tar contains water and light oil and these constituents cause frothing, which occurs as the temperature of the tar rises. This necessitates slow and careful heating or heating under pressure. In the final stages the pitch is a highly viscous liquid and uniform and sufficient heating, so as to expel 10 all oil, is difficult to bring about owing to poor conductivity and sluggish convection currents.

By our method of operation we overcome these difficulties in a continuous manner and 15 finally have to provide for the re-distillation of an oil which does not froth or leave any pitch as residue.

According to our invention, we feed the crude tar, preferably preheated, under the 20 surface of a mass of molten metal maintained at a temperature suitable for volatilizing the volatile constituents, with the exception of anthracene, which remains for the greater part in the residue of distillation, 25 this residue constituting semi-pitch; for this purpose it is preferred to maintain the molten metal at a temperature of about 275-290° C. We withdraw the semi-pitch from the still, and further treat it by raising 30 it to a temperature at which it gives up the anthracene which it contains. We prefer to conduct this latter treatment with the aid of super-heated steam in the form of a jet which breaks up the semi-pitch into spray; the 35 anthracene is carried over by the steam and recovered, and leaves as residue pitch. The period of time during which the tar is under the metal is short but is sufficient to vaporize the water and light oils, which may, if desired, be removed from the still by a separate 40 outlet. We prefer to work in such a way that all the original vapours leave the primary still through one outlet, since by this means we have the advantage of steaming 45 the semi-pitch with the water vapour which is formed while the tar is immersed in the molten metal. This enables us to work at a somewhat lower temperature and assists the removal of the heavier oils. The 50 dehydrated tar is caused to flow over the molten metal surface, taking, it may be a circuitous route owing to baffles, and is here deprived of all the oils which are volatile below the temperature of the molten metal,

say 275° to 290° C. It is preferable that 55 the residue in the still should be as thin a layer as possible.

The volatile constituents of the tar leave the still at a substantially uniform rate and may be fractionally condensed if desired, but 60 we find that fractional condensation involves such large scrubbing vessels that it can only be economically applied when the difference between the fractionating temperatures is 65 very considerable. This is the case with the light fractions and the creosote fraction. We therefore prefer to lead the volatile constituents into a relatively small fractional condenser, the head of which may be kept at about 120° C. by means of the incoming 70 tar which is thus preheated. The vapours leaving at about 120° C. consist almost entirely of water vapour and light oils. There may be some oil boiling above 180° C. that is, creosote oil, but there will be no light oil 75 left in the liquid which condenses in the fractionator which is the important point.

The condensate from the fractionator is now led into a small secondary still also containing molten metal which is kept hot by 80 means of waste heat from the primary still. This secondary still is kept at about 230° C. and removes all the remaining constituents which boil up to 230° C. The distillate is cooled and collected. The residue constitutes another fraction boiling between 230° 85 C. and 270° C.

If desired these temperature limits may be subjected to considerable variation.

The light oil which is always subjected 90 to re-distillation is treated in a subsidiary still where it is heated by means of the latent heat of condensation of one of the higher fractions. In this way a considerable heat economy is effected and a continuous process 95 is substituted for the present intermittent processes.

If desired, we may condense all or part of the vapours from the primary still and re-vaporize them in secondary stills leading 100 the condensate into the highest temperature still first condensing the vapors from each still and leading the condensate into the still having the next higher temperature. The number of separate stills, and the temperatures at which they are maintained will, of course, depend on the number of fractions 105 it is desired to obtain. In this case, we col-

lect the residues from each still as the fractions desired.

This method has some advantages but more heat is required and more condenser space is necessary. Furthermore, corrosion occurs to some extent whenever water condenses owing to the presence of a certain quantity of ammonium chloride. It is desirable, therefore, to limit the points of attack by removing the water at the first condensation and for this reason we prefer the combined fractional condensation followed by re-distillation already described.

It is necessary to provide molten metal bottoms to the secondary stills in case they should for some reason run dry. The molten metal would in such circumstances prevent local overheating and damage to the still.

20 The preferred method of operating according to the invention is as follows:—

The tar is treated by means of the molten metal bath and the temperature of the residue is kept at about 275–290° C. This semi-pitch flows into the base of a tower where a jet of superheated steam breaks it up into a spray. The finely divided pitch gives up its anthracene in presence of the steam and the vapour is led to a condenser. This condenser is kept at about 100° C.–104° C. and serves to condense all the anthracene but allows the steam to pass on. This steam is caused to flow through the superheater again by the action of a jet of high pressure steam and the mixture of high and low pressure steam thus produced is used to spray the pitch. By this means a considerable economy in steam and therefore fuel consumption is effected. The steam acts only as a carrier and there is no objection to the re-use of the steam at a lower pressure. It is sometimes desirable to insert the jets of high pressure steam actually in the spraying tower so that the pitch is sprayed and the low pressure steam induced at this point; the advantage of this method consists in a more perfect subdivision of the pitch.

It is necessary to superheat the steam which is being used to as great an extent as 50 is possible with the flue gases since only the sensible heat of the pitch and the steam is available to supply the latent heat of the anthracene fraction.

It is possible, however, to operate without 55 superheating if provision is made for adding heat to the semi-pitch from some external source.

The accompanying diagram illustrates the invention:—

60 Referring to the drawing the molten metal bath still *a* is set in a furnace *b* and its temperature maintained at about 275–290° C. The tar is pumped from a container *c* by a pump *d* and after passing through a heat exchanger *e* and a jacket to the frac-

tionating column *f*, enters the still *a* beneath the surface of the metal therein. Here it loses all constituents which boil below the aforesaid temperature, which pass as mixed vapours into the column *f*. The temperature of the latter being kept at about 120° C. by the tar passing through the jacket, the vapours which leave the column consist almost entirely of water vapour and light oils: these vapours pass through the heat exchanger *e* and flow by pipe *g* to the condenser *h*.

The constituents free from light oil which condense in the column *f* flow through pipe *i*, heat exchanger *k* and pipe *l* into the secondary still *m* which is also a molten metal bath and is kept at a temperature about 230° C. The vapours from this still pass through the heat exchanger *k* and pipe *n* to the condenser *o*, while the residue from the still flows into a cooler *p*.

The semi-pitch leaves the still *a* by pipe *q* to enter a tower *r* where it is sprayed by superheated steam. The anthracene and steam passes by pipe *s* to the condenser *t* which is at about 100 to 104° C. so that the anthracene condenses and is recovered while the steam is returned to the tower *r* through a superheater; the arrangements for this are not shown in the diagram. The pitch from tower *r* is withdrawn through the pipe *u*.

Having thus described the nature of the said invention and the best means we know of carrying the same into practical effect, we claim:—

1. A process of distilling tar, which consists in feeding the tar under the surface of a mass of molten metal, maintaining the temperature of the molten metal at a temperature adapted to vaporize the more volatile constituents and to leave as residue of the distillation semi-pitch containing the greater part of the anthracene present in the tar, withdrawing from the surface of the metal the semi-pitch produced and raising the temperature of the semi-pitch to that at which it gives up the anthracene which it contains.

2. A process of distilling tar, which consists in feeding the tar under the surface of a mass of molten metal, maintaining the temperature of the molten metal at a temperature adapted to vaporize the more volatile constituents and to leave as residue of the distillation semi-pitch containing the greater part of the anthracene present in the tar, withdrawing from the surface of the metal the semi-pitch produced and causing the semi-pitch to meet a jet of superheated steam so that it is broken up into spray and gives up its anthracene to the steam.

3. A process of distilling tar, which consists in feeding the tar under the surface of a mass of molten metal, maintaining the temperature of the metal above 275° C. and

below 290° C., withdrawing from the surface of the metal the semi-pitch produced and raising the temperature of the semi-pitch to that at which it gives up the anthracene which it contains.

4. A process of distilling tar, which consists in feeding the tar under the surface of a mass of molten metal, maintaining the temperature of the metal above 275° C. and below 290° C., withdrawing from the surface of the metal the semi-pitch produced and causing the semi-pitch to meet a jet of superheated steam so that it is broken up into spray and gives up its anthracene to the steam.

5. A process of distilling tar, which consists in feeding the tar under the surface of a mass of molten metal, maintaining the temperature of the molten metal at a temperature about 275° C. and below 290° C., maintaining the vapors evolved at a temperature adapted to condense at least a part thereof, thereafter bringing the condensate into contact with another mass of molten metal at a temperature adapted to vaporize a fraction of said condensate, and to leave as unvaporized residue another fraction, withdrawing from the surface of the first-mentioned metal the semi-pitch produced and raising the temperature of the semi-pitch to that at which it gives up the anthracene which it contains.

6. A process of distilling tar, which consists in feeding the tar under the surface of a mass of molten metal, maintaining the temperature of the molten metal at a temperature about 275° C. and below 290° C.,

maintaining the vapors evolved at a temperature adapted to condense at least a part thereof, thereafter bringing the condensate into contact with another mass of molten metal at a temperature adapted to vaporize a fraction of said condensate, and to leave as unvaporized residue another fraction, withdrawing from the surface of the first-mentioned metal the semi-pitch produced and causing the semi-pitch to meet a jet of superheated steam so that it is broken up into spray and gives up its anthracene to the steam.

7. A process of distilling tar comprising the following steps—(1) preheating the tar; (2) feeding the pre-heated tar under the surface of molten metal maintained at a temperature above 275° C. and below 290° C.; (3) cooling the vapours which leave the tar to a temperature about 120° C.; (4) feeding the liquid condensate from step (3) beneath the surface of molten metal maintained at a temperature about 230° C.; (5) condensing the vapours not condensed in step (3); (6) condensing the vapours from step (4); (7) withdrawing the non-vaporized residue from the surface of the metal in step (4); (8) withdrawing the non-vaporized residue from the surface of the metal in step (2); and (9) causing the withdrawn residue in step (8) to meet superheated steam so as to volatilize anthracene and obtain hard pitch.

In testimony whereof we have signed our names to this specification.

JOHN STANLEY MORGAN.
